ARTICLE OF HARDWARE

Horace H. Raymond, Berlin, Conn., assignor to
 The Stanley Works, New Britain, Conn., a corporation of Connecticut

Application February 11, 1939, Serial No. 255,805

11 Claims. (Cl. 41—34)

The present invention relates to hardware, and more particularly to a decorative handle suitable for use as a drawer pull, door pull, or the like.

5 The present invention aims to provide an improved handle having a colored portion associated therewith adapted to match with the color scheme of the surroundings where it is used. Due to the modern trend of using decorative 10 articles and the utilization of uniform color schemes throughout the household or the like, there has arisen a large demand for hardware of the above-indicated type. However, as the 15 variety of colors run into extremely large numbers, whereas the demand for any particular color is not known, it has been found impossible for a dealer to carry a stock which will meet all demands. The present invention aims to provide an improved handle or the like wherein any 20 particular color may be associated therewith. This is accomplished by providing a handle having an elongated open faced channel into which a colored insert may be readily inserted and which insert will be secured in place by the 25 mounting of the handle upon the drawer, door, or the like. With this arrangement, a dealer may carry a minimum stock of handles and a maximum stock of colored inserts and thus provide to the ultimate purchaser an unlimited 30 selection. For example, the manufacturer of the handle disclosed herein provides the dealer with a box containing one dozen handles and an envelope containing thirty-six colored inserts in dozen lots of three different colors. Thus the 35 dealer may carry a stock of a dozen handles and yet supply the purchaser with any color desired; it being apparent, of course, that colored inserts other than those contained in the box may be readily obtained. Likewise, if after the 40 handle has been in use for some time and it is desirable to change the colored insert, it is only necessary to remove the handle from the surface on which it is mounted, whereupon the insert may be readily removed therefrom and another 45 replaced therein.

The invention further contemplates a handle which is simple and inexpensive in construction, may have a chromium or other suitable finish which will contrast with the colored insert carried thereby to provide a handle which is very attractive in appearance.

50 Other objects will be in part obvious and in part pointed out more in detail hereinafter.

The invention accordingly consists in the features of construction, combination of elements,

and arrangement of parts which will be exemplified in the construction hereafter set forth and the scope of the application of which will be indicated in the appended claims.

5 In the accompanying drawing: Figure 1 is a side elevation, partly in section, of the handle made in accordance with the present invention;

Figs. 2 to 4, inclusive, are perspective views of the cover member showing the steps in manufac- 10 turing same;

Fig. 5 is a perspective view of the base member with the cover member indicated in dotted lines just prior to final assembly;

Fig. 6 is a fragmentary bottom view of one end 15 of the handle member;

Fig. 7 is a section taken on line 7—7 of Fig. 1; and

Fig. 8 is a perspective view of the colored 20 insert.

Referring to the drawing, the invention comprises a handle of substantially continuous curvature and generally designated as A and adapted to be mounted on the outer surface of a drawer, door, or the like, generally indicated 25 as B. There is provided in the outer face of the handle a channel C coextensive with the length thereof and in which there is positioned a removable insert D of a material which contrasts in appearance with the handle A.

30 In the particular embodiment shown, the handle, for ease in manufacture, is made up of a plurality of parts including a base member 10 and a cover member 12 which are adapted to be assembled into an integral handle structure 35 provided with an elongated open faced channel at its outer surface, as shown in Fig. 1, and a colored insert or strip 14 adapted to be positioned in the channel and be visible through the open face thereof.

40 More specifically, the base member comprises a rigid, relatively heavy one-piece metal strip bent into the shape of a flattened U to provide a central hand gripping portion 16 and rearwardly projecting leg portions 18 adapted to space the 45 central portion outwardly from the surface B of the drawer, door, or the like, on which the handle is mounted. Each leg portion 18 is provided at the end thereof with an inwardly extending securing lug 20 of substantially square 50 cross section and of lesser width than that of the leg portion. The securing lugs 20 are each provided with a centrally located aperture 23 for receiving the end of a suitable securing screw 25 which is passed through the openings provided 55

therefor on the surface on which the handle is mounted. The securing lugs 20 are so arranged that the terminus of the leg portions of the handle will be drawn in and lie flush against the 5 surface on which the handle is mounted. In the embodiment illustrated, this is accomplished by arranging the lugs 20 at substantially ninety degrees to the extremity of the leg portions 18; the arrangement of the lugs depending, of course, 10 upon the particular type of handle desired.

The inner face of the base member 10 is further provided with spaced apart downwardly projecting lugs or detents which may be struck out therefrom to form outwardly facing locking 15 shoulders 26 positioned in substantially vertical alignment with the inner ends of the securing lugs 20 and adapted, as hereinafter described, to interengage with a portion of the cover plate to interengage with a portion of the cover plate to 20 interlock the parts together into an integral structure.

The cover plate 12 consists of a relatively thin flexible metal strip stamped and curved to provide an elongated section 30 adapted to overlie the outer surface of the base member 10 and securing 25 means comprising end closures 31 adapted to be reversely bent around the securing lugs 20 to cooperatively engage the base member locking shoulders 26 and firmly secure the cover plate to the base plate.

30 The securing means or end closures 31 each include a bottom plate 32 bent at right angles to the terminus of the elongated section 30 and adapted to underlie the securing lugs 20; there being provided therein a centrally arranged slot 33 alignable with the lug apertures 23 to permit the securing screw 25 to extend therethrough. Bent upwardly from each bottom plate and at right angles thereto and adjacent the end of the securing lug is an end plate 34 of such length that 35 the upper edge 35 engages behind the outwardly facing locking shoulder 26 on the inner face of the base member 10. To completely enclose the lug, there is provided a pair of side plates 36 bent outwardly and at right angles to the end plate 34 40 to lie parallel against the sides of the securing lugs 20. The outer edges of the end plates are curved to conform to the inner surface of the base member and adapted to abut against same when the parts are locked together and thus 45 substantially brace the vertical end plate 34.

The central portion of the cover member is further provided with a raised rectangular section 39 coextensive in length therewith and centrally positioned intermediate of the side edges thereof 50 and having a top wall 48 and side walls 42. The top wall 48 has cut therein a plurality of elongated narrow slots 45 extending for a greater part of the length thereof; the width of the slots being less than the width of the top wall to provide 55 flanges 43 extending inwardly from the side walls 42 thereof (see Fig. 7). With this construction, the raised section 39 thus cooperates with the base member when the parts are assembled to provide the open faced channel C adapted to receive the colored insert, which insert is readily 60 visible therethrough.

Due to the fact that in the embodiment illustrated the top plate is made of relatively thin metal, portions of the top wall 48 of the section 39 65 have been retained in order to strengthen same; it being apparent, of course, that the open face of the channel could be coextensive in length with the base member were heavier material used or the channel could be formed within the heavier base member. As best seen in Fig. 6, the chan-

nel terminates in end openings 44 of sufficient size to permit the ready insertion of the colored insert D within same.

The colored insert D may be cut from a strip of any suitable material and is of such length that 5 when placed within the channel C it is coextensive in length with the handle. The width of the strip is such that the end thereof may be readily inserted in the end openings 44, whereupon the strip may be slid into position, and, preferably, 10 this width is greater than the slot or open face of the channel, whereby when it is positioned within same the side flanges 43 will overlie the edges thereof and prevent removal of the strip through the open face of the channel. It is apparent that the strip may, however, be readily removed through the open ends 44 and replaced by another strip. However, as previously indicated, when the handle is mounted on a door the securing lugs are so arranged that when the securing 15 screws are inserted therein the handle is drawn to bring the end of the leg portions into engagement with the surface on which the handle is mounted, and thus the end openings 44 will be closed and the colored strip retained in place 20 within the channel.

For convenience in manufacture, the cover member 12 is initially stamped and bent into the form shown in Fig. 2, wherein the bottom plate 32 and end plate 34 of the end closure are coextensive with the elongated section 30 and the side plates 36 bent at right angles to the end plate. The plate is then bent through ninety degrees at the junction of the bottom plate 32 and elongated section 30 to the form shown in Fig. 3. The elongated section 30 is then bent to substantially the curvature of the base member, as indicated in Fig. 4, whereupon the base member is inserted in same, and the end closure substantially completed by bending the end plate 36 at substantially a 40 right angle to the bottom plate 32, as indicated by the dotted lines in Fig. 5. As the cover member is of very thin material, the shaping steps may be performed by hand. As indicated in Fig. 5, the bottom, end, and side plates of the end closure 45 closely engage the abutting surfaces of the securing lug and position the plates relative to one another.

With the parts so assembled and positioned, they are placed in a press, whereupon the cover member will be forced into position around the base member and the upper edges 35 of the end plates 34 forced into locking position behind the locking shoulders 26 to secure the parts into an 55 integral structure.

When so constructed, the colored strip D may be readily inserted in or removed from the channel, whereas when the handle is mounted on a flat surface the end openings 44 of the channel will be closed and the removal of the colored strip 60 therefrom prevented. If, however, it is desirable to change to another color, the handle may be readily removed from the door or the like, and as the new strip is placed in one end opening 44, it 65 will force the old strip out of the other.

The parts are preferably chromium plated or otherwise finished to form a background contrasting with and setting off the colored strip, although any suitable materials which will produce the same result may be used. The strip 70 14 may be of viscoloid or other suitable substance which has a lustrous hard surface, does not readily chip, and is sufficiently flexible to allow it to be inserted within the handle and adjust itself to the curvature thereof.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

15 I claim as my invention:

1. A handle of the character described, comprising a member having an open faced channel in the outer surface thereof and coextensive in length with the member and provided with 20 openings at the ends thereof, a colored strip positioned within said channel and visible through the open face thereof and removable through said end openings, and means for mounting said handle on a surface, whereby when said handle is mounted the end openings will be closed to prevent removal of the strip.

2. A handle of the character described, comprising a member adapted to be secured to a drawer, door, or the like, the outer face of said 30 member being provided with inwardly extending flanges which terminate short of one another to define a channel extending longitudinally of the member and coextensive in length therewith, said channel being provided with open ends at the 35 ends of said member, a colored strip positioned within said channel and visible therethrough and adapted to be readily removed through said end opening, and means for securing said handle on a drawer, door, or the like, whereby the surface 40 on which it is mounted will cover said end opening.

3. A handle of the character described, comprising a member having a central portion and rearwardly extending leg portions adapted to 45 space the central portion outwardly from the surface on which it is mounted, a securing lug extending from the end of each leg portion, said member having a channel extending the entire length thereof, and the outer face of said member being provided with a slot opening into said 50 channel, and a removable strip positioned within said channel and of greater width than said slot.

4. A handle of the character described, comprising a base member adapted to be secured to 55 a drawer, door, or the like, a cover member applied to said base member and having an opening therethrough, and a decorative strip interposed between said members and held in place thereby in alignment with said cover plate openings.

5. A handle of the character described, comprising a base member adapted to be secured to a drawer, door, or the like, a cover member adapted to fit over said base member and having an opening therethrough, cooperating means 65 on said cover member and base member for maintaining said parts positioned relative to one another, and a decorative strip interposed between said members and held in place thereby 70 in alignment with said cover plate opening.

6. In a handle of the character described, a base member adapted to be secured to a drawer, door, or the like, a cover member adapted to 75 overlie the outer surface of said base member and having end portions adapted to be reversely

bent around the ends of said base member to engage the under surface thereof and position said members relative to one another, said cover member having an opening therein intermediate of the end portions, and a decorative strip interposed between said members and held in place thereby in alignment with said cover plate opening.

7. In a handle of the character described, a base member adapted to be secured to a drawer, door, or the like, a cover member adapted to overlie the outer surface of said body member and having end portions adapted to be bent around the ends of said base member to engage the under surface thereof and position said members relative to one another, said cover member having an elongated raised channel extending intermediate of the end portions, a decorative strip positioned in said channel, the outer surface of the channel having openings therein for 20 displaying the colored strip.

8. A handle of the character described, comprising a rigid base member, a securing lug carried at each end thereof and adapted to lie parallel to the surface on which the handle is to be mounted, a relatively thin cover member overlying the outer face of said base member and having a bottom plate adapted to underlie said lugs, said cover member having an opening there-through intermediate of said bottom plate, an end plate extending vertically from said bottom plate and adapted to engage the under surface of said cover member for positioning said members relative to one another, and a decorative strip interposed between said members and held 35 in place thereby in alignment with the cover member opening.

9. In a handle of the character described, a rigid U-shaped base member, said member having securing lugs extending inwardly from each end thereof and at substantially right angles thereto, a thin cover member overlying said base member and having end portions for positioning said cover plate relative to the body member and comprising inturned walls bent at right angles to the ends of the cover member and underlying said lugs, a positioning plate bent upwardly at right angles to the ends of said inturned portions, and side plates bent outwardly at right angles to said positioning plate and straddling 50 said lugs, the outer edges of said side plates and upper edge of said positioning plate abutting against the under surface of said body member, and spaced apart projections on the under face of the base member engaging said plate edges 55 and positioning same against the body member.

10. In combination, a curved elongated base member having a leg portion at one end, a securing lug extending at right angles to the end of the leg portion, a one-piece cover member for 60 said base member comprising a curved elongated section conforming substantially to and adapted to overlie the outer surface of said base member and having a raised lengthwise extending channel provided with a slot, an inturned portion at each end of said elongated portion bent at right angles to the end of said elongated portion and underlying said securing lug, a wall portion bent upwardly and substantially at right angles to each inturned portion and having the upper edge 65 thereof in abutting relation with the under side of said base member, and side portions bent substantially at right angles to the side edge of said wall portions and having their outer edges thereof curved to conform substantially to the 70 75

under side of said base member, said inturned portion, wall portion, and side portions cooperating to enclose said lug, the under side of said base member having a projection extending therefrom and adapted to engage the upper edge of said wall portion and position said base and cover member relative to one another.

11. A handle of the character described, comprising a base member adapted to be secured to a drawer, door, or the like, a cover member

adapted to fit over the outer face of said base member and having end portions adapted to be reversely bent around the ends of said base member and to abut the under face thereof, and interengaging means on the under face of said base member and said end portions for maintaining said members positioned relative to one another.

HORACE H. RAYMOND. 10
